VOLTAGE-CONTROLLED RING OSCILLATORS

Kenneth E. Forsberg, Great Neck, N. Y., assignor to Raytheon Manufacturing Company, Newton, Mass., a corporation of Delaware

Application November 3, 1952, Serial No. 318,439

8 Claims. (Cl. 250—36)

This invention relates to oscillator circuits whose periods of oscillation are linearly controlled by two or more control voltages to determine the oscillatory period.

In many applications involving pulse techniques and counter operations, it is desirable to have a train of pulses having precisely determined, variable pulse duration and repetition rate. In many cases, it is also desirable that such variations be in accord with the variation of one or more control voltages. By the present invention, such an oscillator is made from at least two monostable multivibrators, with the plate of the normally nonconducting tube of one of the multivibrators coupled to the plate of the normally conducting tube of the other multivibrator with controlling voltages coupled to the grid of the normally nonconducting tube of each multivibrator, so that one voltage controls the duration of the output pulse and the other voltage determines the interval between the pulses. In the case of a train of pulses of relatively long duration with respect to the interval between pulses, the voltage applied to such a circuit for determining the duration of the pulses may be considered as a coarse control, in that it controls the larger parameter, and the voltage controlling the interval between pulses as a fine control, in that it controls the smaller interval of time. Such a circuit permits frequency control over a wide range of frequencies. Ranges of from five to one are easily obtainable. Such a circuit is inexpensive to build and maintain as it only requires capacitors and resistors, in addition to the tubes and power sources, and needs no relatively expensive inductances. For this and other reasons, the circuit is particularly useful for the automatic control of low frequency oscillations, particularly square waves. More than two voltages may be used to determine the pulse repetition rate and duration of the wave form by the use of more than two multivibrators in the circuit of this invention.

Other and further advantages of this invention will be apparent as the description thereof progresses, reference being had to the accompanying drawings wherein:

Fig. 1 is a schematic diagram of the circuit of one embodiment of the invention;

Fig. 2a is a time diagram of the wave form appearing at the output of the first multivibrator;

Fig. 2b is a time diagram of the wave form appearing at the output of the second multivibrator;

Fig. 2c is a time diagram of the wave form appearing at the output of the oscillator; and

Fig. 3 is a schematic diagram of a circuit embodying the invention with more than two multivibrators and controlling voltages.

In Fig. 1, the reference numeral 10 represents the normally nonconducting tube of the first multivibrator. This tube has a plate 11, a grid 12, and a cathode 13. The plate 11 is connected to a source 14 of positive potential through a resistor 15. The grid 12 is connected to an input terminal 16. The cathode 13 of the first tube 10 is connected to the cathode 17 of a second tube 18 and to the negative terminal of the source 14 of positive potential through a common resistor 20. The plate 21 of the tube 18 is connected to the source 14 through a resistor 22. The grid 23 of the tube 18 is coupled to the plate

2

11 of the tube 10 through a capacitor 24, and is connected to the source 14 of positive potential through a resistor 25. The plate 21 of the tube 18 is coupled to the plate 26 of a third tube 27 through a capacitor 28. The plate 26 is connected to the source 14 of positive potential through a resistor 30. The grid 31 of the tube 27 is connected to input terminal 32. The cathode 33 is connected to the cathode 34 of a fourth tube 35 and to a common load resistor 36. The plate 26 of the tube 27 is coupled to the grid 37 of the fourth tube 35 through a capacitor 38. The grid 37 of the tube 35 is also connected to the source 14 of positive potential through a resistor 40. The plate 41 is coupled to the plate 11 of the tube 10 through a capacitor 42. The plate 41 is also connected to the source 14 of positive potential through a resistor 43 and to an output terminal 44.

In operation, the tubes 10 and 18 and their associated components constitute a monostable cathode-coupled multivibrator producing a square wave output, such as the wave form 50 in Fig. 2a, at the plate 21 of the tube 18. The duration t_1 of these positive pulses is determined by the voltage E_1 applied at the input terminal 16. This voltage may be the combination of a direct current bias and a triggering pulse. It may also be an adjustable biasing voltage that is made to vary in response to some condition that it is desired to have control the duration and frequency of the pulses at the output of this oscillator. This wave form 50 is applied to the plate 26 of the tube 27 of the second monostable multivibrator through the capacitor 28. The second multivibrator, consisting of tubes 27 and 35 and their associated components, produces a square wave output, such as wave form 51 shown in the graph of Fig. 2b. A control voltage E_2 is applied to the input terminal 32 which determines the duration of these positive pulses t_2 . This wave form 51 appearing at the plate 41 of the tube 35 is coupled back through capacitor 42 to the plate 11 of the tube 10. The result is a wave form 52 appearing at the output terminal 44. It will be seen that the leading edge 53 of the output wave form 52 occurs coincident with the leading edge 54 of the wave form 50, and the duration of the pulse is determined by the pulse duration t_1 . The leading edge 56 of wave form 51 occurs coincident with the trailing edge 55 of wave form 52, and this time is coincident with the termination of the pulse duration t_1 of wave form 50. The pulse duration t_2 determines the time at which the oscillator recycles. This is accomplished by having the multivibrator comprising tubes 10 and 18 trigger the multivibrator comprising tubes 27 and 35 at the end of the first multivibrator's unstable period. In turn, the second multivibrator triggers the first at the end of the second multivibrator's unstable period. The oscillatory period of each multivibrator is related to the applied controlling voltage E_1 or E_2 as follows:

$$T_1 = K_1 E_1$$

$$T_2 = K_2 E_2$$

where K_1 and K_2 are factors dependent upon the fixed parameters of the respective multivibrators.

The period of the resultant wave form is

$$T = K_1 E_1 + K_2 E_2$$

This principle can be extended to any number of multivibrators, as shown in Fig. 3, where the first two multivibrators comprising tubes 110, 118, 127, and 135 are connected in the same manner as the multivibrators comprising tubes 10, 18, 27, and 35, shown in Fig. 1 and described above. The components of these multivibrators have been given the same reference numerals as in Fig. 1 but are preceded by the numeral 1. Additional multivibrators, such as those comprising tubes 160 and 161, have been added. The additional multivibrators are con-

nected in a manner similar to those shown in Fig. 1. The plate 162 of the tube 160 is connected to the source 114 of positive potential through a resistor 163. The grid 164 is connected to an input terminal 165. The cathode 166 is connected to the cathode 167 of the tube 161 and returned to the negative terminal of the source 114 through a resistor 168. The plate 162 is coupled to the grid 169 of the tube 161 through a capacitor 170. The grid 169 is also connected to the source of positive potential 114 through a resistor 171. The plate 172 of the tube 161 is connected to the source of positive potential 114 through a resistor 173. The plate 162 of the tube 160 is coupled to the plate 141 of the tube 135 through a capacitor 175. The plate 172 of the tube 161 is coupled to the plate 110 of the tube 118 through a capacitor 174 and is also connected to an output terminal 144.

In operation, the multivibrators comprising the tubes 127 and 135 trigger the multivibrator comprising tubes 160 and 161 at the end of the second multivibrator's unstable period. In turn, the third multivibrator triggers the first through the capacitor 174 at the end of the third multivibrator's unstable period. Recycling occurs when the first multivibrator triggers the second multivibrator through the capacitor 128 at the end of the first multivibrator's unstable period. As before, the oscillatory period T of each multivibrator is related to the applied controlling voltage E by the factor K . Thus, the overall period of a change in such a ring of multivibrators will be

$$T = K_1 E_1 + K_2 E_2 \dots + K_N E_N$$

The result is a ring oscillator having an output wave form, the repetition rate and pulse duration of which is dependent upon the values of any desired number of voltages each of which may, in turn, be made dependent upon some other condition.

This invention is not limited to the particular details of construction, materials and processes described, as many equivalents will suggest themselves to those skilled in the art. It is, accordingly, desired that the appended claims be given a broad interpretation commensurate with the scope of the invention within the art.

What is claimed is:

1. A voltage-controlled oscillator comprising a plurality of multivibrators arranged in a ring-oscillator circuit, each having a normally conducting and a normally nonconducting electron discharge device having a plate, a grid and a cathode, capacitive means to couple the plate of the normally nonconducting device of each multivibrator except the first to the plate of the normally conducting device of the preceding multivibrator and the plate of the normally nonconducting device of the first multivibrator to the plate of the normally conducting device of the last multivibrator, means to apply a controlling voltage to the grid of the normally nonconducting device of each multivibrator to linearly control the pulse duration and repetition rate of the output.

2. A voltage-controlled oscillator comprising a plurality of voltage-sensitive multivibrators arranged in a ring-oscillator circuit, each having a normally conducting and a normally nonconducting electron discharge device having a plate, a grid and a cathode, capacitive means to couple the plate of the normally nonconducting device of each multivibrator except the first to the plate of the normally conducting device of the preceding multivibrator and the plate of the normally nonconducting device of the first multivibrator to the plate of the normally conducting device of the last multivibrator, means to apply a controlling voltage to the grid of the normally nonconducting device of each multivibrator to linearly control the pulse duration and repetition rate of the output.

3. A voltage-controlled oscillator comprising a plurality of monostable multivibrators arranged in a ring-oscillator circuit, each having a normally conducting and a normally nonconducting electron discharge device having a

plate, a grid and a cathode, capacitive means to couple the plate of the normally nonconducting device of each multivibrator except the first to the plate of the normally conducting device of the preceding multivibrator and the plate of the normally nonconducting device of the first multivibrator to the plate of the normally conducting device of the last multivibrator, means to apply a controlling voltage to the grid of the normally nonconducting device of each multivibrator to linearly control the pulse duration and repetition rate of the output.

4. A voltage-controlled oscillator comprising a plurality of cathode-coupled multivibrators arranged in a ring-oscillator circuit, each having a normally conducting and a normally nonconducting electron discharge device having a plate, a grid and a cathode, capacitive means to couple the plate of the normally nonconducting device of each multivibrator except the first to the plate of the normally conducting device of the preceding multivibrator and the plate of the normally nonconducting device of the first multivibrator to the plate of the normally conducting device of the last multivibrator, means to apply a controlling voltage to the grid of the normally nonconducting device of each multivibrator to linearly control the pulse duration and repetition rate of the output.

5. A voltage-controlled oscillator comprising a pair of multivibrators each having a normally conducting and a normally nonconducting electron discharge device having a plate, a grid and a cathode, capacitive means to couple the plate of the normally nonconducting device of each multivibrator to the plate of the normally conducting device of the other multivibrator, means to apply a controlling voltage to the grid of the normally nonconducting device of each multivibrator to linearly control the pulse duration and repetition rate of the output.

6. A voltage-controlled oscillator comprising a pair of voltage-sensitive multivibrators each having a normally conducting and a normally nonconducting electron discharge device having a plate, a grid and a cathode, capacitive means to couple the plate of the normally nonconducting device of each multivibrator to the plate of the normally conducting device of the other multivibrator, means to apply a controlling voltage to the grid of the normally nonconducting device of each multivibrator to linearly control the pulse duration and repetition rate of the output.

7. A voltage-controlled oscillator comprising a pair of monostable multivibrators each having a normally conducting and a normally nonconducting electron discharge device having a plate, a grid and a cathode, capacitive means to couple the plate of the normally nonconducting device of each multivibrator to the plate of the normally conducting device of the other multivibrator, means to apply a controlling voltage to the grid of the normally nonconducting device of each multivibrator to linearly control the pulse duration and repetition rate of the output.

8. A voltage-controlled oscillator comprising a pair of cathode-coupled multivibrators each having a normally conducting and a normally nonconducting electron discharge device having a plate, a grid and a cathode, capacitive means to couple the plate of the normally nonconducting device of each multivibrator to the plate of the normally conducting device of the other multivibrator, means to apply a controlling voltage to the grid of the normally nonconducting device of each multivibrator to linearly control the pulse duration and repetition rate of the output.
